IMPLANTABLE MEDICAL-ELECTRONIC CARDIAC PACER POWER SOURCE AND ELECTRONIC CIRCUIT SPACER

Howard J. Thompson, New Richmond, Wis., assignor to
Medtronic, Inc., Minneapolis, Minn.

Filed Apr. 26, 1974, Ser. No. 464,485

Term of patent 14 years

Int. Cl. D24—03

U.S. CL. D83—1 F

Fig. 1

Fig. 2

Fig. 3Fig. 4Fig. 5Fig. 6FIG. 1 is a front elevational view of an implantable medical-electronic cardiac pacer power source and electronic circuit spacer, showing my new design;

FIG. 2 is a rear elevational view thereof;

FIG. 3 is a top plan elevational view thereof;

FIG. 4 is a bottom plan view thereof;

FIG. 5 is a left side elevational view thereof; and

FIG. 6 is a right side elevational view thereof.

I claim:

The ornamental design for an implantable medical-electronic cardiac pacer power source and electronic circuit spacer, as shown.
